IMPACT WRENCH

Clifford E. Fitch, Crete, Ill.

Application October 27, 1948, Serial No. 56,701

13 Claims. (Cl. 192—30.5)

1

This invention relates to an impact tool and more particularly to a clutch arrangement for an impact tool by means of which a succession of rotational hammer blows may be imparted through an anvil to a driven member such as a nut, bolt, screw or the like which offers resistance to rotation during a tightening or loosening operation.

It is an object of the invention to provide such a tool wherein breakage of parts during normal use is reduced to a minimum. Devices of this sort in the past have required frequent replacements of broken parts and this results in high maintenance expense and loss of time. The inherent weaknesses in the tool have always been a limiting factor with regard to the amount of impact force available. This present device is not only economical from the standpoint of maintenance but is a more effective impact tool in that it permits greater impact force to be made available.

The foregoing constitute some of the principal objects and advantages of the present invention, others of which will become apparent from the following description and the drawings, in which

Fig. 1 is a longitudinal sectional view through the impact mechanism forming the subject matter of the present invention, showing the same attached to a motor that is illustrated in elevation;

Fig. 2 is a transverse sectional view through the impact mechanism, the view being taken on the line 2—2 of Fig. 1 and illustrating the hammer locks in a neutral position;

Fig. 3 is a view corresponding to Fig. 2 but illustrating the hammer locks in striking position;

Fig. 4 is a view corresponding to Fig. 2 but illustrating the hammer locks in reset position prior to application of the striking force;

Fig. 5 is a longitudinal sectional view through the impact mechanism, the view being taken on the line 5—5 of Fig. 1;

Fig. 6 is a transverse sectional view through the impact mechanism, the view being taken on the line 6—6 of Fig. 5; and

Fig. 7 is a transverse sectional view of the impact mechanism, the view being taken on the line 7—7 of Fig. 5.

For purposes of illustration a single embodiment of the invention is shown in the drawings and will be described hereinafter. It is recognized, of course, that many modifications may occur to the man skilled in the art and it is

2

intended that such modifications may be made in the embodiment shown without departing from the intended scope and spirit of the invention.

5 Referring now to the drawings the present invention is illustrated in the form of an impact tool generally illustrated at 15 that includes a motor portion 16 which for purposes of illustration may be a compressed air motor. The 10 invention is not limited to this type of motor, however, as an electric motor as well as other types will serve equally well. The motor 16 as shown is provided with a flange portion 17 to which is attached by means of screws 18 a housing 19. This housing 19 includes a clutch assembly generally indicated at 20.

The details of the motor 16 are unimportant insofar as concerns the present invention inasmuch as they form no part of the invention

20 For present purposes it is necessary merely to disclose a motor shaft 21 that is driven by the motor and is splined as at 22 to an upper plate or cage member 23 that is contained in the housing 19. This upper plate or cage member 23 is disposed in the upper region of the housing 19 and is bolted by means of bolts 24 to a lower plate or clutch member 25.

25 Mounted between the upper and lower plate or cage members 23 and 25 is an anvil 26 that is provided with a downwardly projecting shank portion 27 that projects through an aperture 28 in the lower plate 25. This shank 27 of the anvil 26 projects through an aperture 29 provided in the lower face of the housing 19, and to the lowermost end of the shank 27 as at 30 may be attached a screw driver, socket or other type of tool to which the impact is to be applied.

30 Also mounted between the upper and lower plates 23 and 25 is a pair of roller locks 31, each of which is pivotally mounted on one or the other of the bolts 24 so that each of the roller locks 31 can rock back and forth about its respective bolt 24. When the two roller locks 31 are in their positions shown in Fig. 2 they form 35 in effect substantially a complete circular unit with their abutting ends spaced only a very small distance apart. Both the upper and the lower plates 23 and 25 are provided with a pair of oppositely disposed radial grooves 32, the grooves 40 in the upper plate 23 being aligned with the grooves in the lower plate 25. A pair of impact rollers 33 extend vertically between the upper and lower plates 23 and 25 and project at their opposite ends into the radial grooves 32 in the 45 upper and lower plates 23 and 25 respectively.

These rollers 33 are adapted to ride in the grooves 32 radially with respect to the plates 23 and 25.

As shown in Fig. 2 each of the roller locks 31 is arcuate in shape and is provided adjacent to each of its ends on its inner face with an outer arcuate seat portion 34 and an inner arcuate seat portion 35. The inner face of each roller lock 31 throughout the major portion of its length is substantially circular as at 36 but is provided with a cam projection 37 located on one side of the adjacent bolt 24 forming the pivot for the roller lock and a second cam projection 38 located on the other side of the bolt 24. The anvil 26 is substantially completely surrounded by the cooperating roller locks 31 and when the hammer locks are in the position shown in Fig. 2 they are disposed concentrically about the anvil 26.

The anvil 26 is substantially cylindrical in form but is provided with a pair of oppositely disposed radially extending lobes 39. As shown in Fig. 5 the shaft 21 of the motor is bored at 40 and the upper part of the anvil 26 is bored as at 41 to receive a centering pin 42 that centers or guides the anvil with respect to the upper plate 23. Each impact roller 33 is held between the outer arcuate seat portion 34 of the adjacent roller locks 31 and the adjacent lobe 39 of the anvil 26 and under these conditions the complete assembly including the roller locks 31, the bolts 24 and the upper and lower plates 23 and 25 are free to move as a unit about the anvil 26 carrying with them the impact rollers 33 that move over the arcuate outer surfaces of the lobes 39 of the anvil 26.

In Fig. 3 the elements are shown in their position for driving the anvil 26 directly from the driven shaft 21 of the motor. In the position shown in Fig. 4 the elements are shown in an intermediate position where the anvil 26 is stationary and the roller locks 31 are being rotated at a relatively high velocity along with the upper and lower plates 23 and 25 respectively prior to the application of the impact that takes place at the time the elements assume the position shown in Fig. 3.

For purposes of explaining the operation of the present device let it be assumed that a socket of the normal socket wrench type is secured to the lower end of the shank 27 of the anvil 26. It will be assumed that the operation to be performed is the tightening of a nut on a bolt. The socket is first applied over the nut and the tightening operation is commenced. Shaft 21 is rotated by the motor 16 and under these conditions the parts will be disposed in the position shown in Fig. 3. The drive from shaft 21 is effected through upper plate 23 (Fig. 1), through bolts 24, lower plate 25, through the roller locks 31, impact rollers 33 and finally to the anvil 26. Thus the motor 16 is connected to the nut and rotates the nut toward its tightening condition. When the nut first reaches its initial tightened condition a resistance to turning is imparted to the anvil 26. This causes the anvil 26 to force the impact rollers 33 outwardly in their respective grooves 32 until the rollers 33 climb over the corresponding lobes 39 on the anvil 26. When this occurs the elements are in the position shown in Fig. 2, so that the anvil 26 is now allowed to remain at rest while the remaining elements making up the striking assembly rotate about the anvil. When the cam projections 37 reach the adjacent lobes 39 on the anvil 26 they rock their respective roller locks 31 to the position shown in Fig. 4 which represents a reset condition for the roller locks

prior to the application of the impact that follows. The roller locks 31 with their remaining assembly continue to rotate about the stationary anvil 26 until the cam projections 38 reach the respective lobes 39 of the stationary anvil 26 at which time roller locks 31 are caused to rock in the opposite direction at a high rate of speed to the position shown in Fig. 3 where the roller locks 31 engage the impact rollers 33 to force the rollers into their innermost positions in their respective grooves 32 and then the entire kinetic energy of the moving cage including the upper and lower plates 23 and 25 together with the roller locks 31 on their pins or bolts 24 is given up in the form of an impact force against the lobes 39 of the anvil 26. This force is exerted from plates 23 and 25 through the sides of grooves and the rollers 33 onto the anvil lobes 26. The roller locks in their positions shown in Fig. 3 hold rollers 33 in position to strike anvil lobes 39. This impact force imparts an additional tightening force onto the nut following which the operation is repeated.

The reverse shock subjected by the anvil 26 against the impact rollers 33 is transmitted by the rollers 33 in most part to the edges of the grooves 32 of upper and lower plates 23 and 25. Only a very small portion of this reverse shock is transmitted through the roller locks 31 so that neither the roller locks 31 nor the bolts 24 are subjected to heavy shock loading during normal operation of the present device. This represents a distinct advantage over prior devices of this nature because the roller locks 31 and their respective bolts 24 are relatively fragile as compared with the upper and lower plates 23 and 25 and thus, the breakage is reduced to a minimum.

It is to be noted that the anvil 26 as shown in Figs. 2 to 4 inclusive is symmetrical about its vertical axes. Each of the roller locks 31 is symmetrical about its transverse axis passing through the center of bolt 24. Thus the device will operate when the motor shaft 21 is rotated in either clockwise or counterclockwise direction.

I claim:

1. An impact mechanism comprising a rotary anvil, a striking lobe on the anvil, a rotary impact member rotatable independently of the anvil, an intermediate member movable between the impact member and the anvil lobe for transmitting the impact load from the impact member to the anvil lobe, and lock means carried by the impact member and operated by the anvil for positively moving the intermediate member.
2. An impact mechanism comprising a rotary anvil, a striking lobe on the anvil and an impact assembly mounted concentrically about the anvil and rotatable independently of the anvil, the assembly comprising spaced upper and lower plate members, lock means between the plate members, pivot means mounting the lock means on the plate members so that the lock means can rock about said pivot means, and an intermediate member engageable by the roller lock means to be maintained in position to engage the anvil lobe for transmitting the impact load from the impact assembly to the anvil lobe, the lock means being adapted to rock from a position where it engages the intermediate means to maintain the latter in the path of the anvil lobe to a withdrawn position.
3. An impact mechanism comprising a rotary anvil, a striking lobe on the anvil and an impact assembly mounted concentrically about the anvil and rotatable independently of the anvil, the as-

sembly comprising spaced upper and lower plate members, lock means between the plate members, pivot means mounting the lock means on the plate members so that the lock means can rock about said pivot means, and an intermediate member mounted to slide radially between the upper and lower plates and adapted in one position to engage the anvil lobe, the lock means being adapted to rock from a position where it engages the intermediate means to maintain the latter in the path of the anvil lobe to a withdrawn position.

4. An impact mechanism comprising a rotary anvil, a striking lobe on the anvil and an impact assembly mounted concentrically about the anvil and rotatable independently of the anvil, the assembly comprising spaced upper and lower plate members, lock means between the plate members, pivot means mounting the lock means on the plate members so that the lock means can rock about said pivot means, a radial groove in each of the upper and lower plates, an intermediate member, the intermediate member projecting into the grooves, the intermediate member being adapted to slide in the grooves and in one position to lie in the path of the anvil lobe while at the same time being engageable by the lock means, the lock means being adapted to rock from a position where it maintains the intermediate means in the path of the anvil lobe to a withdrawn position.

5. An impact mechanism comprising a rotary anvil, a striking lobe on the anvil and an impact assembly mounted concentrically about the anvil and rotatable independently of the anvil, the assembly comprising spaced upper and lower plate members, lock means between the plate members, pivot means mounting the lock means on the plate members so that the lock means can rock about said pivot means, a radial groove in each of the upper and lower plates, an intermediate member, the intermediate member projecting into the grooves, the intermediate member being adapted to slide in the grooves and in one position to lie in the path of the anvil lobe while at the same time being engageable by the lock means, the lock means being adapted to rock from a position where it maintains the intermediate means in the path of the anvil lobe so as to exert a striking force against the lobe to a withdrawn position, the direction of the striking force against the anvil lobe being transverse with respect to the grooves.

6. An impact mechanism comprising a rotary anvil, a striking lobe on the anvil and an impact assembly mounted concentrically about the anvil and rotatable independently of the anvil, the assembly comprising spaced upper and lower plate members, roller lock means between the plate members, pivot means mounting the roller lock means on the plate members so that the roller lock means can rock about said pivot means, and an elongated roller extending between the upper and lower plates and fixed to rotate with the plates, the roller lock means being adapted to engage the roller, the roller being adapted to engage the anvil lobe for transmitting an impact load from the impact assembly to the anvil lobe, the roller lock means being adapted to rock from its position where it engages the roller when the latter is in engagement with the anvil lobe to a withdrawn position to permit the roller to clear the anvil lobe.

7. An impact mechanism comprising a rotary anvil having a striking portion, and a rotary im-

pact assembly comprising an upper and a lower plate sandwiching the anvil therebetween, a pair of substantially semi-circular roller locks sandwiched between the plates and mounted to form

5 together substantially a circle, pivot means disposed substantially in the center of each semi-circular roller lock securing the roller locks to the upper and lower plates but permitting rocking of each roller lock about its pivot from an impact position to a neutral position, an intermediate impact roller disposed between the abutting ends of the roller locks and the anvil and adapted to clear the anvil striking portion when the roller locks are disposed in neutral position, and cam
10 means on each roller lock adapted to engage the anvil to rock the roller lock from neutral position to impact position, the intermediate impact roller being adapted to strike the anvil striking portion and concurrently being disposed in engagement with the roller lock when the latter is disposed in its impact position.

8. An impact mechanism comprising a rotary anvil having a striking portion, and a rotary impact assembly comprising an upper and a lower plate sandwiching the anvil therebetween, a pair of substantially semi-circular roller locks sandwiched between the plates and mounted to form together substantially a circle, pivot means disposed substantially in the center of each semi-circular roller lock securing the roller locks to the upper and lower plates but permitting rocking of each roller lock about its pivot from an impact position to a neutral position, an intermediate impact roller fixed to rotate with the upper and lower plates and mounted to move radially on the plates, the intermediate impact roller being disposed between the abutting ends of the roller locks and the anvil and adapted to clear the anvil striking portion when the roller locks are disposed in neutral position, and cam
25 means on each roller lock adapted to engage the anvil to rock the roller lock from neutral position to impact position, the intermediate impact roller being adapted to strike the anvil striking portion and concurrently being disposed in engagement with the roller lock when the latter is disposed in its impact position.

9. An impact mechanism comprising a rotary anvil, an impact hammer member, an impact roller between said anvil and impact hammer member, a locking member actuated by said anvil positively to move the impact roller into locking position at a predetermined position.

10. An impact mechanism comprising a rotary anvil, a striking lobe on the anvil, an impact assembly mounted concentrically about the anvil and rotatable independently of the anvil, impact transmitting means between the anvil and the impact assembly, and means actuated by the anvil positively to move the impact transmitting means into the path of the anvil lobe.

11. An impact mechanism comprising a rotary anvil, a striking lobe on the anvil, an impact assembly mounted concentrically about the anvil and rotatable independently on the anvil, impact transmitting means between the anvil and the impact assembly, and means controlled by the anvil for positively moving the impact transmitting means into impact position at a predetermined position of the impact assembly with respect to the anvil.

12. An impact mechanism comprising a rotary anvil, a striking lobe on the anvil, an impact assembly mounted concentrically about the anvil and rotatable independently of the anvil, impact

rollers carried by the impact assembly and controlled by the anvil, and roller locks on the impact assembly positively to move the impact rollers into a striking position with respect to the anvil lobes for transmitting the impact load from the impact assembly to the anvil lobes.

13. An impact mechanism comprising a rotary anvil, a striking lobe on the anvil, an impact assembly mounted concentrically about the anvil and rotatable independently of the anvil, impact rollers carried by the impact assembly, roller locks carried by the impact assembly and movable from a neutral position to a locking position where they engage the impact rollers for positively moving and locking the impact rollers into

striking position with the anvil lobes for transmitting the impact load from the impact assembly to the anvil lobes, and cam members on the roller locks adapted to be actuated by the anvil lobes to move the roller locks between their two positions.
